UNITED STATES PATENT OFFICE.

FRANK E. WOOD AND CLARENCE G. WOOD, OF GIRARD, PENNSYLVANIA.

ARTICLES SECURED TO WIRE AND METHOD OF SECURING SAME.

1,397,848.

Specification of Letters Patent.

Patented Nov. 22, 1921.

Application filed October 1, 1919. Serial No. 327,656.

To all whom it may concern:

Be it known that we, FRANK E. WOOD and CLARENCE G. WOOD, citizens of the United States, residing at Girard, in the county of Erie and State of Pennsylvania, have invented new and useful Improvements in Articles Secured to Wire and Methods of Securing the Same, of which the following is a specification.

10 In the manufacture of many articles, particularly toys, it is common to secure wheels and different articles to wire rods or axles. Various methods have been provided for securing such articles to wire. The present 15 invention relates to an improved method of securing objects to wire and to the article so formed.

The invention is illustrated in the accompanying drawings as follows:

20 Figure 1 shows a fragment of wire.

Fig. 2 a portion of the dies for swaging the wire.

Fig. 3 a side elevation of the swaged wire.

Fig. 4 a cross section on the line 4—4 in

25 Fig. 3.

Fig. 5 a side elevation of an article to be secured to the wire, in this instance a small sheet metal disk.

Fig. 6 a section on the line 6—6 in Fig. 5.

30 Fig. 7 an alternative construction of disk.

Fig. 8 a section on the line 8—8 in Fig. 7.

Fig. 9 an elevation showing the disk in place prior to securing it on the wire.

Fig. 10 a section of a fragment of the dies

35 in position to operate on the wire and disk.

Fig. 11 a side elevation, partly in section, showing the completed article.

Fig. 12 a construction in which the plate and disk are laminated.

40 1 marks the wire, 2—2 the swaged ribs on the wire, 3 a metal disk, and 4 the opening through the disk.

The wire as shown in Fig. 1 is first put under the dies 5—5 having the portions 6—6

45 conforming to the surface of the wire and the side parts 7—7 for swaging the wire to form the ribs 2, thus distorting or changing the cross section of the wire. The disk is formed in the usual manner by a punching

50 machine and threaded on the wire as shown in Fig. 9. The wire is then placed in the openings 8—8 in the dies 9—9. These dies preferably have a slight cup 10 adjacent to the opening on the face. As the dies are

55 closed the ends of the wires contact the ends of the openings 8 and the wire is located

when the dies complete their movement so that approximately the center of the swaged portion of the wire is at the face of the dies. As the dies advance the disk is forced on to 60 the swaged portion, thus making its own key-way and the swaged portion of metal is forced outwardly on the face of the disk forming shoulders 11 on each face of the disk, thus not only locking the disk against 65 rotation on the wire but securing it thereto. The disk preferably has a slight off-set at its center and the protruding part of this off-set is in advance as the parts are forced together in the manner shown in Fig. 10. 70 This slight depression assures a position of the metal plate forming the metal disk in advance of the upsetting action on the swage portion 2 of the metal. While this is preferable and gives a greater shoulder at this 75 side of the disk the shoulders will be formed and the disk secured even though the disk be entirely flat.

In Figs. 7 and 8 we show the disk with an opening 4^a, the opening having slots 12 80 conforming to the rib 2. Possibly if the plate were extremely heavy this might be desirable but with the ordinary thickness of plate we have used in dies we have found that the opening 4 conforming to the general shape of the wire operates perfectly.

In some instances it is desired to have the plate 3 laminated. In Fig. 12 it is so shown, the two parts 3^a being metal plates and the central plate 3^b being of paper. This is 90 forced on in exactly the same manner and secured in the same manner, the only difference in process being that the movement of the dies should be adjusted to allow for the added thickness of the laminated plate. 95

What we claim as new is:

1. An article of manufacture comprising a wire; and a plate secured on the wire, the portion of the wire within the plate having a distorted cross section, and portions of the 100 wire being swaged out and against the sides of the plate.

2. An article of manufacture comprising a wire; and a laminated plate secured on the wire, the portion of the wire within the plate 105 having a distorted cross section, and portions of the wire being swaged out and against the sides of the plate.

3. The method of securing wire to articles which consists in swaging a portion of the 110 wire to change its cross section, forming the article with an opening therein, forcing the

article on to the swaged portion, and forcing the swaged metal outwardly and against the sides of the article.

4. The method of securing wire to articles which consists in swaging a portion of the wire to change its cross section, forcing the article onto the swaged portion, and simultaneously forcing the swaged metal outwardly and against the sides of the article.

10 5. The method of securing wire to articles which consists in swaging a portion of the wire to change its cross section, placing an article on the wire, placing the wire in dies having openings conforming to the general 15 cross section of the wire, closing the dies to force the article on to the swaged portion of the wire and to upset the swaged portion of the wire against the sides of the article.

6. The method of securing wire to articles which consists in swaging a portion of the wire to change its cross section, placing an article on the wire, placing the wire in dies 20 having openings conforming to the general

cross section of the wire, closing the dies to force the article on to the swaged portion of the wire and to upset the swaged portion of the wire against the sides of the article, one hole of the dies being limited to position the swaged portion with relation to the dies.

7. The method of securing wire to articles which consists in swaging a portion of the wire to change its cross section, placing an article on the wire, placing the wire in dies having openings conforming to the general cross section of the wire, closing the dies to force the article on to the swaged portion of the wire and to upset the swaged portion of the wire against the sides of the article, the holes of both dies being limited to position the swaged portion of the wire with 35 relation to the face of the dies.

In testimony whereof we have hereunto set our hands.

FRANK E. WOOD.
CLARENCE G. WOOD.
